UNITED STATES PATENT OFFICE.

HIERONYMUS PAUL SCHUTTLER, OF CHARLOTTENBURG, GERMANY.

TWO-STROKE-CYCLE INTERNAL-COMBUSTION ENGINE.

Application filed January 25, 1924. Serial No. 688,576.

To all whom it may concern:

Be it known that I, HIERONYMUS PAUL SCHUTTLER, a German citizen, of Charlottenburg, Germany, have invented certain new and useful Improvements Relating to Two-Stroke-Cycle Internal-Combustion Engines, of which the following is a specification.

This invention relates to two-stroke cycle internal combustion engines and has for its object to provide for the more complete charging of the engine cylinder or cylinders with combustible mixture at each stroke, and for the more effective expulsion of the burnt gases or products of combustion without admixture of the same with the combustible charge.

The invention comprises the improved construction of engine and combinations and arrangements of parts hereinafter described and claimed.

Referring to the accompanying sheets of explanatory drawings:—

Figure 1 is a sectional elevation of a two stroke cycle engine constructed in one convenient form in accordance with my invention.

Figure 2 is a sectional plan view on the line AB of Figure 1.

Figure 3 is a sectional elevation of the upper part of an engine showing a modified construction of same.

Figure 4 is a sectional elevation on the line DEF of Figure 5, and Figure 5 a sectional plan view on the line GH of Figure 4 showing a further modified construction of engine.

The same reference letters in the different views indicate the same or similar parts.

Referring in the first place to Figures 1 to 2, the engine proper comprises a piston *a* having a sleeve or skirt like extension *b* thereon which slides within an annular recess provided between the cylinder wall *c* and the cylinder head *d*. The skirt *b* has ports *e* therein for placing the interior of the back of the piston in communication with the exhaust ports *f* and ports *g* for placing the said interior of the piston in communication with the transfer passages *h* by which the combustible charge from the engine crank case is passed into the said piston. The carburettor *i* supplies the crank case with a combustible charge for compression purposes in the known manner each time the piston *a* rises or moves outwards.

The cylinder head *d* is ribbed as shown to

assist in the radiation of heat therefrom and is adapted to receive a sparking plug at its centre, as shown by dotted lines. The end of the skirt *b* upon the piston *a* acts as a piston within the annular recess in which it works and on the in or downstroke of the piston tends to create a vacuum in said annular recess. The ports *j* in the cylinder walls are of such small dimensions that such vacuum is only partially destroyed by a withdrawal from the transfer passage *h*, so that when the piston reaches or approaches the end of its inward or power stroke, there is still a considerable degree of vacuum in said annular recess. This is broken by air drawn therein through the ports *k* in the cylinder head. The effect of the rush of air through the ports *k* is to cause an inflow of fresh air to the interior of the cylinder head which cools the said head. The circulation of air in the said recess and through the ports *j* also tends to keep the skirt or sleeve *b* cool.

If desired, I may as shown in Figure 3, fit a non-return valve *u* upon each passage *j* so that during the power stroke of the piston *a*, a vacuum is formed in the annular recess before referred to until the ports *k* are uncovered, when air is admitted to said recess. During the return stroke of the piston, free delivery takes place of pure air into the passages *h*. The non-return valves *u* each consist of a disc with an adjustable stop piece *v* for limiting the opening movement of the disc.

Due to the formation of the piston *a* with a sleeve portion *b*, the area of the piston at the crank case side which acts to pump and compress the combustible charge is greater than the effective area of the opposite side of the piston so that a full charge or a super-charge is received by the engine at each stroke under full power conditions, that is when the crank chamber is receiving a full charge.

It will be seen that by arranging two transfer ports *h* at opposite sides of the cylinder near the end face of the cylinder head *d* in which the sparking plug is fitted, and the exhaust ports *e* at opposite sides of the piston near its lower end, I obtain a uniform flow effect through the cylinder, the charging taking place at one end and exhaustion at the other end. By this means, expulsion of the exhaust gases without admixture with the combustible charge is ob-

tained, and the sparking plug is placed in the zone of the united incoming streams, so that proper ignition and combustion of the charge is ensured.

5 In the arrangements shown in Figures 4 and 5, I provide for the admission to a single transfer passage *h* of a small charge of air from the space within the cylinder head by way of a port *g* in the said head, a port *r* in 10 the sleeve or skirt *b* upon the engine piston and a channel *s* formed around the engine cylinder and leading to the said transfer passage *h*. With this construction, when the piston *a* is approaching the end of its 15 outward stroke and the combustible charge is being drawn into the crank chamber, the ports *g* and *r* come into line and air is drawn into the channel *s* and transfer passage *h*. When, therefore, the transfer passage is put 20 into communication with the port *g* in the sleeve or skirt *b*, practically pure air passes first into the piston followed by the combustible charge. The said pure air assists in the expulsion of the products of combustion 25 from the piston and prevents contamination or admixture of the combustible charge with the same.

It will of course be understood that instead of compressing a combustible charge 30 in the engine crank case, I may compress pure air only therein and mix the fuel therewith as it passes into the engine piston or in the transfer passages. Ordinary and well known methods of adding fuel to the air 35 consist of (1) balanced carburetors each spraying into a Venturi tube through which the air enters the engine piston and (2) spray nozzles, each with a pump appropriately timed to inject fuel into the engine at 40 the correct instant.

I claim:—

1. In a two-stroke cycle internal combustion engine, a cylinder, a crank chamber, a head extending into the cylinder and having a 45 portion spaced from the latter to provide an annular recess between the head and cylinder, a spark plug disposed within said head, a piston in said cylinder having a sleeve thereon working in said annular recess, a transfer passageway for leading fuel compressed in the crank chamber to the interior of the cylinder, and means whereby the piston sleeve controls the admission of external air to the transfer passageway and permits

said air to enter the engine cylinder before 55 the ordinary combustible mixture charge enters the cylinder from said passageway.

2. In a two stroke cycle internal combustion engine as claimed in claim 1, the sleeve snugly fitting in the annular recess so as 60 to produce a partial vacuum in the recess during the outward stroke of the piston, means for admitting air into the annular recess at about the end of the outward stroke of the piston, and a conduit for transferring 65 air admitted to said annular recess, to said transfer passageway.

3. In a two stroke cycle internal combustion engine as claimed in claim 1, the sleeve snugly fitting in the annular recess so as to 70 produce a partial vacuum in the recess during the outward stroke of the piston, means for admitting air into the annular recess at about the end of the outward stroke of the piston, a conduit for transferring air admitted to said annular recess, to said transfer passageway and a non-return valve in the conduit to permit air to be forced from the annular recess into the transfer passageway but preventing air from passing from 75 the transfer passageway into said recess.

4. In a two-stroke cycle internal combustion engine, a cylinder, a head extending into the cylinder and having a portion spacing from the latter to provide an annular 80 recess between the head and cylinder, a piston in said cylinder having a sleeve thereon working in the annular recess, two inlet ports in said sleeve at diametrically opposite points, two exhaust ports in said sleeve 85 also at diametrically opposite points and spaced circumferentially between the said inlet ports, two inlet ports, a crank chamber, transfer passageways in the cylinder leading from the crank chamber and adapted to 90 introduce a compressed combustible mixture from the crank chamber through said inlet ports into the cylinder, a spark plug port arranged centrally within the cylinder head, and means whereby the piston sleeve causes 95 the circulation of atmospheric air through the cylinder head and controls the passage of the combustible mixture from the transfer passageways to the interior of the cylinder.

In testimony whereof I have signed my 100 name to this specification.

HIERONYMUS PAUL SCHUTTLER.
